HAIR TRIMMING AND SHAVING
ATTACHMENT FOR COMBS

Benedetti Di Zazzo, Syracuse, N. Y.

Application January 19, 1951, Serial No. 206,855

10 Claims. (Cl. 30—31)

1

The present invention relates to improvements in a hair trimming and shaving attachment for a comb and has for an object the provision of a device of this kind which is adapted to be quickly mounted upon and removed from a hair comb.

Another object of the present invention is to provide an improved razor attachment which is especially adapted to be demountably attached to the type of comb disclosed in my prior U. S. Patent No. 2,481,403, granted September 6, 1949, for a Barber Comb.

A further object of the present invention is to provide an improved device of this character which is capable of being adjusted so that the size of the cuts may be selectively varied.

A still further object of the present invention is the provision of an improved razor attachment for combs with which the hair of a person may be cut, trimmed, thinned and shaved and also combed at the same time.

Still another object of the present invention is the provision of a device of this type which can be efficiently used not only by skilled persons, such as barbers, and operators of beauty parlors, but also by unskilled persons and even by children.

The present invention aims to provide an improved razor attachment for combs which comprises relatively few parts and is economical to manufacture.

In one of its broadest aspects the present invention contemplates the provision of an improved razor attachment for a hair comb comprising a mounting member for attachment to a hair comb, a clamping plate associated with said member, and means carried by said plate and adapted to clamp a razor blade against the teeth of the comb when the razor blade is positioned between said plate and the teeth of the comb.

More specifically the present invention contemplates the provision of an improved razor attachment for a hair comb comprising a mounting member of substantially inverted U-shape and having a bridge portion, a pair of spaced apart legs depending from the bridge portion, a flange extending upwardly, rearwardly and downwardly from the bridge portion for engaging over the back of the comb and a hook extending rearwardly and upwardly from the lower end of each leg for engaging the free end portions of the teeth of the comb, a guide portion member on each leg of the mounting member and each comprising a strip attached to its leg and a second strip overlying a portion of the space between

2

said legs, a clamping plate vertically adjustably mounted between said guide members and having a screw threaded opening therein, a boss extending from the forward face of said plate and having a screw threaded bore in alignment with the opening in the plate, lugs projecting from the rear face of said plate to be received by the slots in a razor blade when the razor blade is placed between the plate and the comb, a screw received by the opening in the plate and the bore in the boss and adapted to be projected beyond the rear face of said plate to engage the razor blade and to force the razor blade against the teeth of the comb and to force the forward faces of the opposite marginal end portions of said plate against said second strips of the guide members, whereby the clamping plate and the razor blade will be firmly held in place, the lower end portion of each of said second strips being curved downwardly and rearwardly to be disposed in the path of the downward movement of said plate.

With the foregoing and other objects in view, the invention will be hereinafter more fully described and more particularly pointed out in the appended claims.

In the drawings, in which the same parts are denoted by the same reference numerals throughout the several views,

Figure 1 is a front perspective view of the improved device constructed in accordance with the present invention and illustrated as applied to a hair comb;

Figure 2 is a rear perspective view of the improved device;

Figure 3 is a rear perspective view of the clamping plate;

Figure 4 is a vertical sectional view taken through the center of the device shown in Figure 1;

Figure 5 is a sectional view taken on the line 5—5 of Figure 4 and looking in the direction of the arrows.

Referring more particularly to the drawings, 10 generally indicates the improved razor attachment which may be applied to the conventional type of hair comb but in the present illustration is shown as mounted on a comb generally indicated as 11 of the construction disclosed in my prior U. S. Patent No. 2,481,403 mentioned above. Only the large end portion of the comb is shown, but as is well known in hair combs of this type the back or body 12 of the comb 11 progressively increases in width from the smaller end of the comb towards the large end 13 thereof. From the lower edge of the back 12, a group of spaced

apart teeth 14 depend having tapering side walls 15 and 16.

The back or body portion of the comb is formed with a portion 17 extending beyond the edge of the body to which the teeth are affixed and laterally outwardly from the teeth. The inner surface or portion 18 of this extending portion 17 is inclined at a relatively sharp angle toward the center of the toothed edge of the body, thereby forming a knife-like ledge 19 extending continuously along the entire length of the teeth 14. As clearly shown in Figure 4 of the drawings, the ledge or marginal edge 19 of the extended portion 17 defines a recess or space 20 between the inclined surface 18 and the adjacent surfaces 21 of the teeth.

The improved razor attachment 10 comprises a mounting member 22 and a clamping plate 23 which may be made of metal, plastic or any other suitable material. The mounting member may be of substantially inverted U-shape and has a bridge portion 24 and a pair of spaced apart legs 25 depending from the opposite end portions of the bridge portion 24 to provide a space 25a therebetween. A substantially semi-circular flange 26 extends from the upper edge of the bridge portion upwardly, rearwardly and downwardly for engaging over the back 12 of the comb. A hook 27 extends from the lower end of each of the legs 25 rearwardly and upwardly for engaging the free end portions of the teeth 14 of the comb.

A guide member 28 is attached to each of the legs 25 and each guide member comprises a pair of strips 29 and 30 arranged in stepped formation with the strip 29 attached to the forward face of its leg in any suitable manner and a portion of the strip 30 overlying the adjacent outer side area of the space 25a. The strips of each guide member 28 may be formed integral or they may be secured together in any appropriate manner and the guide members may be formed of steel, plastic or other suitable material.

The clamping plate 23 which is more clearly shown in Figure 3 of the drawings may be of substantially oblong shape and has a substantially centrally disposed screw threaded opening 31 therethrough. A boss 32 extends from the forward face of the plate 23 and has a screw threaded bore 33 extending therethrough in alignment with the opening 31 of the plate. A pair of spaced apart lugs 34 are positioned on each side of the opening 31 and extend from the rear face of the plate 23. The lugs 34 are of substantially the same size and shape as the slots 35 of a conventional type of razor blade 36 by which they are adapted to be received. A screw 37 is received by the bore 33 of the boss 32 and is adapted to be threaded into the opening 31 of the plate 23 to have its inner end portion to project beyond the rear face of the plate. The diameter of the screw 37 is larger than that of the hole 38 in the razor blade 36 so that when the razor blade is mounted on the lugs 34 of the plate 23 the inner end of the screw 37 will engage the areas of the razor blade which surround the hole 38 of the blade. The lower edge of the plate 23 may be beveled as at 39 and the lower end portion of each of the strips 30 of the guide members 28 may be curved downwardly and rearwardly as at 40 to engage the beveled lower edge 39 of the plate 23 when it is in its lowermost position.

In the use of the device, the mounting member 22 is slid upon the comb 11 from the small end

thereof so that the flange 26 of the member 22 will engage over the back 12 of the comb and the hooks 27 will engage over the lower portions of the teeth 14. The member 22 is moved along the back 12 of the comb towards the large end 13 of the comb until the flange 26 has a tight fit with the back 12. The razor blade 36 will then be placed upon the rear face of the clamping plate 23 with the lugs 34 disposed in the slots 35 of the razor blade. The plate and the razor blade will then be inserted into the upper ends of the guide members 28 between the strips 30 and the teeth 14 of the comb with the razor blade next to the teeth 14. The user will adjust the plate and the razor blade to the proper height on the mounting member 22 dependent upon the depth of the cut of the hair desired. For the purpose of assuring the proper adjustment, one of the strips 30 may be provided with a vertical column or scale of indicia 41, such as 1, 2, 3 and 4, and the front face of the plate 23 may have an index 42, such as an arrow, formed thereon for association with the indicia 41 to indicate various cutting positions of the razor blade.

When the proper cutting position of the plate and blade has been obtained, they may be locked in this position by turning the screw 37 while holding the plate and the blade until the blade 36 is urged into engagement with the teeth 14 of the comb. Further turning of the screw 37 in the same direction will cause the plate 23 to back up on the screw against the strips 30 as illustrated in Figure 4 of the drawings. In this position of the parts, the blade will be frictionally held against the teeth 14 of the comb against movement and the plate will be held frictionally against the strips 30 against movement. The lugs 34 are of sufficient depth that they cannot escape from the slots 35 of the blade 36 when the plate 23 is backed up away from the blade but the lugs 34 will be received in the spaced between adjacent teeth 14 of the comb to engage therewith to augment the clamping action of the plate and screw in preventing rotation of the razor blade and the plate.

The device is now ready to use for cutting the hair and the user will grasp the small end portion of the comb 11 in his hand and pass the comb and razor attachment downwardly with the lower edge of the blade contacting the hair of the person having his hair cut. The extending portion 17 of the comb will be disposed towards the hair to be cut. After the hair has been cut, the razor attachment may be removed by loosening the screw 37 until the lugs 34 can be withdrawn from between the teeth 14 of the comb and the member 22 will then be slid towards the small end of the comb and removed therefrom. The comb may then be used to comb and set the hair.

If a woman desires to prepare her own hair for a home permanent she will invert the comb 11 and comb a section of her hair about three inches square. The user will hold the tip of each swatch or portion of hair which she desires to thin and shape. The comb will be inverted and the razor blade passed down on the swatch of hair from the top and shape and thin under and over. When the thinning, shaping and cutting operation have been finished, the user will remove the razor attachment and use the comb to finish the setting of the hair.

When the plate and blade is adjusted so that the arrow 42 points to the 1 of the scale 41, the

device is set for shaving the back of the neck, the hair on the legs or the hair under the arms. When the plate and blade are adjusted so that the arrow points to the 2, 3 or 4 of the scale, correspondingly larger cuts will be made. By inverting the comb, the comb may be used for combing down the hair to prepare it for another cut and at the same time cleaning the section of hair that has already been cut. The smaller end portion of the comb provides a comfortable grip, affords greater cleanliness and effects a saving of time.

It will be noted that all kinds of double edge razor blades can be used on the attachment.

It is obvious that various changes and modifications may be made in the details of construction and design of the above specifically described embodiment of this invention without departing from the spirit thereof, such changes and modifications being restricted only by the scope of the following claims.

What I claim is:

1. An improved razor attachment for a hair comb comprising a mounting member for attachment to a hair comb, a clamping plate independent of and loosely supported by said member, and means carried entirely by said plate and adapted to clamp substantially the entire area of one side of a razor blade against the teeth of the comb when the razor blade is positioned between said plate and the teeth of the comb, said means comprising a movable element adapted to engage directly against the razor blade to cause the razor blade to directly and frictionally engage the teeth of the comb.

2. An improved razor attachment as claimed in claim 1 characterized by the fact that said clamping plate is provided with means for permitting relative adjusting movement of said clamping plate and said clamping means and for retaining said plate and said clamping means in their relative adjusted positions.

3. An improved razor attachment for a hair comb comprising a mounting member for attachment to a hair comb, a clamping plate loosely supported by said member and having a screw threaded opening therethrough, and a screw mounted in said opening for directly engaging a razor blade when the razor blade is positioned between said plate and the teeth of the comb, whereby the screw when rotated in one direction will clamp the razor blade against the teeth of the comb and will back said plate up against said mounting member.

4. An improved razor attachment for a hair comb comprising a mounting member for attachment to a hair comb, a clamping plate loosely supported by said member and having a screw threaded opening therethrough, and a screw mounted in said opening for directly engaging a slotted razor blade when the razor blade is positioned between said plate and the teeth of the comb, whereby the screw when rotated in one direction will clamp the razor blade against the teeth of the comb and will back said plate up against said mounting member, and lugs on said clamping plate adapted to be received by the slots in the razor blade.

5. An improved razor attachment as claimed in claim 4 characterized by the fact that said lugs are adapted to be received between adjacent teeth of the comb when the razor blade is clamped against the comb with the free end portions of the lugs positioned entirely within the confines of said adjacent teeth.

6. An improved razor attachment for a hair comb comprising a substantially inverted U-shaped mounting member comprising a bridge portion, a pair of spaced apart legs depending from the bridge portion, a flange extending upwardly, rearwardly and downwardly from the bridge portion for engaging over the back of the comb and frictionally gripping the back of the comb, and a hook extending rearwardly and upwardly from the lower end of each leg for engaging the free end portions of the teeth of the comb, a guide member on each of said legs, a clamping plate vertically adjustably mounted between said guide members, and means carried by said clamping plate for clamping the razor blade against the teeth of the comb and for clamping said plate against said guide members when the razor blade is positioned between said plate and the teeth of the comb.

7. An improved razor attachment for a hair comb having a back which progressively increases in width from one end to the other end comprising a mounting member having a portion adapted to be slid upon the end of the comb having the smaller width and moved along the back of the comb towards the end having the greatest width until said portion of said member tightly grips the back of the comb, said member also having a pair of spaced apart legs, a guide member on each of said legs and each comprising a strip attached to its leg and a second strip overlying a portion of the space between said legs, a clamping plate adjustably mounted between said guide members, a razor blade carried by said plate in the space between said legs, means carried by said plate for clamping said blade against the teeth of the comb and for frictionally holding said plate against said second strips when the blade is clamped against the teeth of the comb.

8. An improved razor attachment for a hair comb comprising a mounting member of substantially inverted U-shape and having a bridge portion, a pair of spaced apart legs depending from the bridge portion, a flange extending upwardly, rearwardly and downwardly from the bridge portion for engaging over the back of the comb and a hook extending rearwardly and upwardly from the lower end of each leg for engaging the free end portions of the teeth of the comb, a guide portion member on each leg of the mounting member and each comprising a strip attached to its leg and a second strip overlying a portion of the space between said legs, a clamping plate vertically adjustably mounted between said guide members and having a screw threaded opening therein, a boss extending from the forward face of said plate and having a screw threaded bore in alignment with the opening in the plate, lugs projecting from the rear face of said plate to be received by the slots in a razor blade when the razor blade is placed between the plate and the comb, a screw received by the opening in the plate and the bore in the boss and adapted to be projected beyond the rear face of said plate to engage the razor blade and to force the razor blade against the teeth of the comb and to force the forward faces of the opposite marginal end portions of said plate against said second strips of the guide members, whereby the clamping plate and the razor blade will be firmly held in place, the lower end portion of each of said second strips being curved downwardly and rearwardly to be disposed in

the path of the downward movement of said plate.

9. An improved razor blade attachment for a hair comb comprising a mounting member comprising a bridge, a leg extending downwardly from each opposite end portion of said bridge, a substantially arcuate shaped flange extending from said bridge for engaging over the back of the comb for frictionally gripping the back of the comb, a hook extending rearwardly and then upwardly from the lower free end portion of each leg for engaging the free end portions of adjacent teeth of the comb, and a guide member on each of said legs, a clamping plate for carrying the razor blade and mounted between said guide members for vertical adjustment with respect to the teeth of the comb, a scale on one of said guide members, an index on said clamping plate for cooperating with said scale to indicate various cutting positions of the razor blade, and means carried by said clamping plate for clamping the razor blade against the teeth of the comb and for clamping said plate against said guide members in the preselected vertically adjusted cutting position of the razor blade and plate.

10. For use with a hair comb having a ledge on its back, an improved razor attachment adapted to be mounted on the comb and comprising a mounting member having a bridge por-

tion and a flange extending rearwardly and downwardly from the bridge portion, the downwardly extending portion of the flange being substantially parallel to the bridge portion and spaced therefrom a distance slightly less than the width of the back of the comb, said bridge portion and flange being adapted to be slid upon the back of the comb to frictionally grip the back therebetween, a clamping plate independent of and loosely supported by the mounting member, a razor blade, and means carried entirely by said plate and directly engaging the blade and adapted to clamp the blade against the teeth of the comb on the side thereof opposite the ledge and below the ledge.

BENEDETTI DI ZAZZO.
